DESIGN FOR A COMBINED WATCH CASE AND WRIST BAND

Robert A. Barré, New York, N. Y.

Application August 8, 1947, Serial No. 140,779

Term of patent 7 years

(Cl. D42—8)

To all whom it may concern:

Be it known that I, Robert A. Barré, a citizen of the United States of America, residing in the city of New York, county of Queens, and State of New York, have invented a new, original, and ornamental Design for a Combined Watch Case and Wrist Band, of which the following is a specification, reference being had to the accompanying drawing, forming part thereof, wherein:

Fig. 1 is a plan view of a combined watch case and wrist band in an interlocked position, showing my new design;

Fig. 2 is a similar view of the same, shown with the band clasp open; and

Fig. 3 is an edge view of the same, with the clasp partly open.

The essential features of the design reside in the watch case and the band linkage thereto.

I claim:

The ornamental design for a combined watch case and wrist band, substantially as shown and described.

ROBERT A. BARRÉ.
